United States Patent

Des. 235,863
Patented July 15, 1975

235,863

AUTOMOBILE WHEEL

James Kresl, Jr., 3924 Pine Ave.,
Long Beach, Calif. 90807

Filed July 5, 1974, Ser. No. 486,179

Term of patent 14 years

Int. Cl. D12—16

U.S. CL. D12—205

FIG. 1

FIG. 2

FIG. 3

FIG. 4

FIG. 1 is a perspective view of an automobile wheel embodying my new design;

FIG. 2 is a side elevational view thereof;

FIG. 3 is a side elevational view thereof opposite to that shown in FIG. 2; and

FIG. 4 is a vertical sectional view thereof taken on line 4—4 of FIG. 3.

I claim:

The ornamental design for an automobile wheel, substantially as shown.
